Specification for Design.

Patented Aug. 22, 1922.

Application filed April 3, 1922. Serial No. 1,519. Term of patent 14 years.

To all whom it may concern:

Be it known that I, CHARLES TWEEDIE, a citizen of the United States, and a resident of Jefferson City, county of Cole and State of Missouri, have invented a new, original, and ornamental Design for a Boot Top, of which the following is a specification.

In the accompanying drawing, which forms part of this specification,

The figure is a side view of a boot top embodying the design, the boot top being shown in position on a shoe which is indicated in dotted lines.

I claim:

The ornamental design for a boot top, as shown.

CHARLES TWEEDIE.
